HARRY WALTER ADAMS, OF FARGO, NORTH DAKOTA, ASSIGNOR OF ONE-HALF TO PHILIP W. FARNHAM, OF FARGO, NORTH DAKOTA.

PISTON-VALVE FOR INTERNAL-COMBUSTION ENGINES.

No. 867,933.

Specification of Letters Patent.

Patented Oct. 8, 1907.

Original application filed July 11, 1905, Serial No. 269,154. Divided and this application filed November 21, 1906.
Serial No. 344,394.

To all whom it may concern:

Be it known that I, HARRY WALTER ADAMS, a citizen of the United States, and a resident of Fargo, in the county of Cass and State of North Dakota, have invented a new and Improved Piston-Valve for Internal-Combustion Engines, of which the following is a full, clear, and exact description.

This invention relates to certain improvements in internal combustion engines, and more particularly to valves designed for use in the piston thereof, and adapted for controlling the passage of air or other gases to or from the piston cylinder; this application being a division of my previous application, Serial No. 269,154, filed July 11, 1905.

15 The object of this invention is to provide means whereby air or an explosive mixture may be admitted to the piston cylinder through the piston thereof, or whereby the exhaust gases of the cylinder may be removed through the piston to the outside atmosphere.

20 The specific valve disclosed in the accompanying drawing is especially adapted for the admission of compressed air to the cylinder for the scavenging of the same, and for permitting the removal of the remainder of the exhaust gases after the first scavenging operation.

25 The general engine structure illustrated in connection with the improved valve and valve operating mechanism is entirely independent thereof, and said valve may be employed in various other engines, and for accomplishing other results than those hereinafter specifically referred to.

In illustrating the construction and operation of my improved valve, I have shown it in connection with an engine having a differential piston, in the end of which is located a port controlled by my improved valve.

35 The piston operates within a differential cylinder and closed crank case in such a manner that at the end of the expansion or working stroke, said valve will be opened and the compressed air within the crank case admitted to the working cylinder to scavenge the same.

40 The pressure within the crank case is thus reduced substantially to that of the atmosphere, and upon the in stroke of the piston the air in the crank case is rarefied and the piston valve is opened to permit of the withdrawal of the remainder of the exhaust gases from the

45 piston cylinder into the crank case to complete the scavenging operation. In the specific engine shown the larger portion of the differential piston serves in connection with certain devices constituting no portion of the invention herein claimed, to compress the air

50 which is led to the admission port of the working cylinder. During the in stroke after the piston valve is closed and the admission port valve is opened, the whole or a part of this compressed air mixed with the fuel

is admitted into the working cylinder and compressed therein during the later portion of the in stroke of the 55 piston.

Reference is to be had to the accompanying drawing forming a part of this specification, and which illustrates as an example the preferred embodiment of my invention, such illustration being a central longitudinal 60 section.

The engine illustrated in the drawing comprises a working cylinder 10 having an enlarged extension 11 forming a compressor cylinder, the latter being in open communication with the crank case 12. Within the 65 working cylinder is a working piston 14 and within the compressor cylinder is a compressor piston 15, which pistons are formed integral but of different diameters, as indicated in the drawing. The pistons are connected by a rod 16 with the crank disks 17 of the shaft 18, 70 and the working piston 14 has a cap 19 bolted thereto, said cap being formed with a tubular stem guide 20 which projects through an opening in the piston toward the crank case. Said guide has openings 21 therein placing it in communication with the crank case, and 75 the upper end of the guide 20 is open and commanded by a valve 22 which opens into the working cylinder. The stem 23 of this valve passes through the guide 20, and has a nut 24 on its lower end engaged by a spring between the nut and the lower end of the guide 20, so 80 as to yieldingly seat the valve 22.

Fitted loosely in and extending longitudinally through the connecting rod 16 is a valve-operated rod 26 having a button 27 on its upper end which engages the nut 24. The lower end of the connecting rod is 85 formed with an annular channel 28 which receives loosely a cam 29 fastened to the wrist pin 30 and adapted to engage the lower end of the valve-operating rod 26. It will thus be seen that the valve 22 is yieldingly seated, is capable of opening automatically upon superior pressure, and is opened once during each revolution of the shaft 18 by the cam 29 striking the valve rod 26, lifting the same, and opening the valve 22 through its stem 3. This periodical mechanical operation of the valve 22 occurs once during each revolution of the crank 95 shaft.

The enlarged compressor cylinder 11 has an air admission port 31 therein, said port being located near the top center or innermost position of the piston, so that it is uncovered only when the piston is at or near the top 100 center position. Upon the downward stroke of the piston air is compressed in the crank case, and when pressure is relieved in the working cylinder, the valve 22 is automatically opened, permitting this air to flow into the working cylinder to scavenge it. Upon the upward 105 movement of the piston the air in the crank case is rare-

fied, and during the inward stroke the valve 22 is mechanically opened through the action of the cam 29 and its coacting parts, thus permitting such products of combustion as may yet reside in the working cylinder 5 to flow into the crank case.

The working cylinder 10 is provided with an admission port 32 and an exhaust port 33, the former being located adjacent the end of the cylinder and communicating with the compression space of the working cylinder 10, while the latter is at the outer or bottom center position of the piston so as to be uncovered only adjacent the end of the working stroke and communicate with the atmosphere. The admission of the air through the port 32 is controlled and governed in any suitable manner, 15 as, for instance, by the mechanism illustrated, such mechanism being clearly described and its operation set forth in the parent application of which this application is a division, and the air admitted to the cylinder 11 through a valve 33^a is compressed and delivered 20 through a valve 34 and a cooler 35 to a suitable carburetor, and thence through a pipe 36, the mechanism for governing and controlling these valves being also fully set forth in the parent application above referred to.

The operation of the engine as far as it relates to the 25 scavenging of the working cylinder may be traced as follows: Assuming the parts to be in the position shown in the drawings and the crank shaft revolving in the direction indicated by the arrow, upon a downstroke or working stroke of the piston the port 31 is covered and 30 compression takes place in the crank case. This continues until the piston reaches a point adjacent the end of its working stroke, that is, until the exhaust port 33 of the working cylinder is opened. At this time the pressure in the working cylinder falls to that of the atmosphere, 35 due to the escape of the exhaust gases through the port 33, and as the pressure within the crank case is now considerably greater than that of the atmosphere, the compressed air within the crank case overcomes the action of the spring 25 and blows into the working cylinder to scavenge it. The pressure of the air within the 40 crank case then drops merely to that of the atmosphere, and as soon as the inward movement of the piston begins, the valve 22 is closed and the air within the crank case is rarefied. The cam 29 now serves to positively 45 open the valve 22 and permit such products of combustion as may yet reside in the working cylinder to flow into the crank case. As the cross sectional area of the compressor cylinder 11 is greater than the cross sectional area of the working cylinder 10, it will be noted that the 50 return movement of the piston toward the working cylinder 10 serves to rarefy the air, and the products of com-

bustion will thus be almost completely withdrawn into the crank case. At or approximately at the middle of the instroke the valve 22 is permitted to close and at this time the admission valve 32 is opened and the air 55 which has been highly compressed between the two pistons 14 and 15 and charged with the fuel at the carburetor, is admitted to the working cylinder. The explosive charge thus enters the cylinder under high pressure, and its entrance to the cylinder is facilitated 60 by the rarefied condition within the working cylinder. During the remainder of the instroke of the piston the charge is still further compressed, and at or near the end of said stroke the charge is ignited and burned in the usual manner. 65

Having thus described my invention, I claim as new and desire to secure by Letters Patent:

1. An internal combustion engine having a working piston, an extended, hollow, perforated, tubular member carried thereby, said piston having a passage therethrough communicating with the interior of said tubular member, a valve for controlling the flow of fluid through said passage, a valve rod for said valve slidably mounted within the outer end of said tubular member, an enlarged curved head secured to the outer end of said valve rod, means intermediate said head and said tubular member for resiliently holding said valve in its closed position, and means in operative engagement with the crank shaft and having an enlarged curved head adapted to engage with the head of the valve rod to intermittently open the valve one of 75 said heads being longitudinally adjustable to control the extent to which said valve is opened.

2. An internal combustion engine having a working piston provided with a passage extending therethrough, a valve for controlling said passage, a perforated tubular member carried by said piston and forming an extension for said passage, a valve rod for said valve supported and guided within said tubular member, a head on the end of said valve rod and longitudinally adjustable in relation thereto, means for resiliently holding said valve in its 80 closed position, and means in operative engagement with the crank shaft for engaging with said head of the valve rod to open the valve, the extent to which the valve is opened being dependent upon the adjustment of said head. 85

3. An internal combustion engine having a working piston provided with a passage extending therethrough, a valve for controlling said passage, a valve rod for said valve, means carried by said piston for supporting and guiding said valve rod, an enlarged head upon the outer end of said valve rod and longitudinally adjustable in relation thereto, and means in operative engagement with a moving part of the engine for engaging with said head to intermittently open said valve. 95

In testimony whereof I have signed my name to this specification in the presence of two subscribing witnesses. 105
